O. Drake, Atty.

UNITED STATES PATENT OFFICE.

SAMUEL A. WEBB, OF NEWARK, NEW JERSEY.

FINGER-PROTECTOR.

SPECIFICATION forming part of Letters Patent No. 268,578, dated December 5, 1882.

Application filed July 26, 1882. (No model.)

To all whom it may concern:

Be it known that I, SAMUEL A. WEBB, a citizen of the United States, residing at Newark, in the county of Essex and State of New Jersey, have invented certain new and useful Improvements in Finger-Protectors; and I do hereby declare the following to be a full, clear, and exact description of the invention, such as will enable others skilled in the art to which it appertains to make and use the same, reference being had to the accompanying drawing, and to letters of reference marked thereon, which forms a part of this specification.

The object of this invention is to protect the finger of the left hand, over which the cloth is stretched in ordinary hand-sewing from being punctured by the needle operated by the right hand.

The invention consists in a thimble or finger protector the outer surfaces of which are smooth or devoid of the usual roughened surfaces.

The drawing herewith connected illustrates said finger-protector, in which said protector is shown with a smooth surface devoid of punctures or other impressions by which the nee-

dle-point would be prevented from sliding smoothly thereover.

Said protector is preferably thimble shape, and is adapted to be placed upon the forefinger of the left hand. Being smooth upon its whole outer surface, when the said thimble is placed in position upon the hand and cloth stretched thereover in the same manner as it is ordinarily stretched over the bare finger, the needle glides thereover readily and freely, and is prevented from injuring the finger or roughening the skin thereof by repeated pricking.

Having described my invention, what I claim is—

An improved article of manufacture—to wit, the finger-protector, the same being a metallic thimble with its entire outer surface smooth—as set forth.

In testimony that I claim the foregoing I have hereunto set my hand this 8th day of July, 1882.

SAMUEL A. WEBB.
